UNITED STATES PATENT OFFICE

THEODORE W. DAHLQUIST, OF DEDHAM, MASSACHUSETTS

HOT WATER BOILER

Application filed October 10, 1929. Serial No. 398,742.

This invention relates to a hot water boiler of that type employing a gas or like fuel burner located below the bottom of the boiler.

The invention has for its object to increase the efficiency of hot water boilers of the type referred to, whereby the water therein may be more economically and quickly heated.

To this end, the boiler is provided with an extension which projects beyond the bottom of the boiler, and said extension has co-operating with it a tubular body which is of smaller diameter than said extension and co-operates therewith and with the bottom of the boiler to form a heating chamber, which is provided with a relatively large gas inlet formed by said tubular body, and is provided with a smaller gas outlet which is formed by the tubular body and said extension, said smaller gas outlet being located below the bottom of the boiler to cause the flow of gases to be reversed as they pass through the heating chamber and also to throttle the flow of the gasses out of the heating chamber and thereby cause the gases in the heating chamber to be maintained in contact with the bottom of the boiler for a substantial length of time and thus more effectively and economically heat the water in the boiler.

The tubular body also forms a combustion chamber within which is located a burner for gas, oil, or like fuel.

The tubular body may and preferably will be attached to the boiler extension and separated therefrom by spacing devices.

The particular features of the invention will be pointed out in the claims at the end of this specification.

Fig. 1 represents one form of hot water boiler embodying this invention, and

Fig. 2, a section on the line 2—2, Fig. 1.

Referring to the drawings 10 represents a hot water boiler such as now commonly used in kitchens of households and like places. The boiler 10 is provided with the usual cylindrical shell or body portion 12 having at its upper end a head (not shown) and at its lower end a bottom 13. The bottom 13 is located within the lower end of the boiler shell 12 to provide the latter with a portion

14 which extends below the bottom 13 and forms a skirt for the boiler.

In accordance with the present invention, the skirt or extension 14 of the boiler shell has co-operating with it a tubular body 15, 55 preferably of metal and cylindrical in shape and of smaller diameter than the skirt 14, which forms with the said skirt an annular passage 16 (see Fig. 2), which connects the space or chamber 17 with the atmosphere. 66

The chamber 17 forms a heating chamber which is closed at its top and sides by the bottom 13 and skirt 14 of the boiler and is in open communication at its lower end with the tubular body 15 and with the atmosphere. 65

The tubular body 15 forms a combustion chamber 20 in which is located a burner 21 for gas, oil, or like fuel, and said burner is provided with a fuel inlet pipe 22 which is connected with a suitable source of supply 70 not shown.

The tubular body 15 may be secured to the skirt 14 of the body by rivets 23 or other fastening devices and separated by spacing bushings 24 through which the rivets 23 are passed 75 in the construction herein shown.

The combustion chamber 20 may be closed at its lower end by a bottom plate 25 which is supported upon the usual pedestal 26.

In the present instance the boiler 10 is provided with an insulating jacket comprising two cylindrical metal members 27, 28 and an interposed layer 29 of heat-insulating material, and said jacket is shown as of sufficiently large diameter to form an annular 80 heating flue or passage 30 for the length of the boiler, through which the products of combustion pass after they leave the heating chamber 17.

The combustion chamber 20 is provided 90 with suitable air inlets for supporting combustion, and the bottom plate 25 may be provided with holes 32 for this purpose.

The boiler herein shown is provided with a cold water inlet pipe 33 and with a hot water outlet pipe 34 and also with a thermostatic device 35 for automatically controlling the supply of gas or other fuel to the burner. The gas inlet pipe 22 is provided with a manually operated valve 36 and with an auto- 100

matic valve which is conventionally represented at 37 and which is controlled by the thermostatic device 35, which is also conventionally represented. These parts are well known and are in common use in hot water boilers and form no part of the present invention.

In operation the products of combustion from the burner 21 flow upwardly from the combustion chamber 20 into the heating chamber 17 wherein they contact with the bottom 13 of the boiler and their flow is then reversed and they flow downward and pass through the outlet passage 16 to the outside 15 of the boiler and then through the passage 30 to the atmosphere when the boiler is provided with the insulating jacket herein shown.

When the boiler is not provided with the insulating jacket, the products of combustion pass through the outlet passage 16 directly into the atmosphere. As the flow of the products of combustion are reversed in the heating chamber and caused to flow downward therein to the outlet passage 16 therefore, the said products of combustion are throttled or retarded in their passage out of the heating chamber, inasmuch as the area of the outlet passage 16 is materially less than the area of the inlet for the heating chamber, which inlet is formed by the tubular body 15.

As a result of this construction and arrangement, the products of combustion are retained in contact with the bottom of the boiler or a greater length of time than would be the case if their flow was not reversed and throttled, and consequently a greater quantity of heat is transferred to the water in the boiler and the water therein is more quickly and economically heated.

It may be preferred to secure the tubular body 15 to the skirt or extension 14 of the boiler shell as herein represented, but it is not desired to limit the invention in this respect, as the tubular body may be welded or otherwise attached at its lower end to the plate 25 and have its upper end disconnected from the skirt 14 of the boiler.

One construction embodying the invention is herein shown, but it is not desired to limit the invention to the particular construction shown.

What is claimed is:—

1. The combination with a hot water boiler having a body portion provided with a bottom and with a skirt projecting below said bottom, of a burner located below said bottom, and a tubular sheet metal member forming a combustion chamber for said burner and having its upper end projecting into the said skirt and secured thereto and separated therefrom to form an outlet passage for a heating chamber formed by said boiler bottom, extension and tubular sheet metal member, said

outlet passage being located sufficiently near the bottom of the boiler to cause said tubular sheet metal member to direct the combustion gases against the bottom of the boiler prior to their escape through said outlet passage.

2. The combination with a hot water boiler having a body portion provided with a bottom and with a skirt projecting below said bottom, of a tubular body co-operating with said skirt and with the bottom of the boiler to form a heating chamber having a substantially large gas inlet formed by the tubular body and a smaller gas outlet formed by the tubular body and said skirt, said tubular body having its upper end arranged with relation to said skirt to obstruct the free flow of gases from the combustion chamber to the outside of the boiler and cause said gases to flow upwardly beyond said outlet into said heating chamber and then downward therefrom through the smaller gas outlet to the outside of the boiler, whereby the bottom of the boiler is subjected to the action of a maximum quantity of hot gases moving through the heating chamber in contact with the bottom of the boiler before passing through said gas outlet.

In testimony whereof, I have signed my name to this specification.

THEODORE W. DAHLQUIST.
